STEAM GENERATOR

Filed Jan. 24, 1930

INVENTOR
*Samuel Paul,
By Archwoth Martin,
Attorney.*

UNITED STATES PATENT OFFICE

SAMUEL PAUL, OF PITTSBURGH, PENNSYLVANIA

STEAM GENERATOR

Application filed January 24, 1930. Serial No. 423,046.

My invention relates to steam generators, and more particularly to those of the portable type.

One object of my invention is to provide a boiler unit of such form that it may be conveniently transported, as by a hand truck or the like, and which nevertheless has considerable steam generating capacity.

Another object of my invention is to provide a steam generator of such form that steam at considerable pressures can be produced more quickly than in the case of generators of various other types.

Another object of my invention is to provide a steam generator having a boiler shell with improved means cooperating therewith to support heating coils and the boiler proper.

A further object of my invention is to provide a steam generator with an improved burner and heating coil arrangement.

Still another object of my invention is to simplify and improve generally the structure and operation of steam generators.

One form which by my invention may take is shown in the accompanying drawing, wherein Figure 1 is a side elevational view of the apparatus; Fig. 2 is a vertical sectional view taken at right angles to Fig. 1, and Fig. 3 is a sectional view, on an enlarged scale, of a portion of the apparatus of Fig. 2.

While the apparatus is herein shown and described as employed for the generation of steam, it will be understood that it may be also employed as a water heater.

The apparatus is particularly suitable for use where a light weight portable steam generating unit is desired, as around garages, to secure steam under pressure, for cleaning and flushing gear cases, etc., of automobiles. To this end, I show the apparatus as mounted upon a two-wheeled hand truck 4. A fuel tank 5, for gasoline or other suitable fuel is shown as secured to the truck frame by a strap 6, while a boiler shell 7 is secured to the truck frame by a strap 8. A burner 9 is provided within the boiler shell 7 and is supplied with fuel from the tank 5, through the conduits, 10, 11 and 12.

The conduit 10 has an extension 13 that

serves to supply a pilot flame at 14. The pilot flame not only serves to ignite the fuel issuing from the burner 9 but heats the conduit 11 so that when fuel is permitted to issue from the burner 9 by opening a valve 14', it will be vaporized to such an extent as to readily be ignited by the pilot flame. The fuel is supplied under air pressure that is maintained within the tank 5, the air under pressure being introduced into the tank in any suitable manner as for instance through a tire valve 15. An air-pressure gage 16 is provided on the tank. Pressure within the tank may suitably be in the neighborhood of twenty pounds.

A boiler 17 is mounted within the shell 7 and a supply of water is maintained therein, the water level being at some point within a gage glass 18 so that a space will be left within the upper portion of the boiler 17 for steam.

The boiler 17 may be initially nearly filled with water and replenishment of the water supply will not be required for a considerable period, thus avoiding the necessity of having permanent hose connection to the boiler.

Two coils 19 and 20 surround the boiler. The coil 19 has its turns interspersed with the turns of the coil 20. The lower end of the coil 19 has communication with the interior of the boiler as indicated more clearly in Fig. 3, and a water supply conduit 21 also communicates with the interior of the boiler at this point. The upper end of the coil 19 communicates with the boiler through an extension 22, in a manner similar to its connection at the lower end of the boiler.

The coil 20 communicates at its upper and lower ends with the interior of the boiler, through extensions 23 and 24, respectively, and these branch-like extensions 23 and 24 of the boiler communicate through nipples 25 and 26, respectively, with the gage glass 18. The nipple members 25 and 26 and nipple members 27 and 28 serve to firmly support the boiler and the coils in the shell 7. The burner flame impinges against the bottom of the boiler 7 and the heat therefrom passes up alongside of the boiler, in contact with the coils 19 and 20.

A heat-insulating lining is provided for the boiler shell 7 to prevent radiation of heat through the shell. The water, when subjected to heat, of course circulates upwardly through the coils 19 and 20 and is rapidly heated by reason of the large amount of coil surface. The double coil arrangement not only serves as a convenient means for connecting the coils and the boiler to the water intake and to the gage, but also facilitates circulation of the water, so that the turns of each coil are of twice the pitch that would be possible with a single coil having turns equal in number to the sum of the turns of the two coils. I therefore disclose a structure wherein in a large number of coil turns are provided within a given space, and wherein the pitch or steepness of the turns is such that more rapid circulation of the water is possible than if the coil turns were of smaller pitch.

The steam which is formed by the water passing through the heated coils accumulates in the boiler 17 and is conducted therefrom through a nipple 30, to a pipe 31. A steam-pressure gage 32 has connection with the nipple 30, and a poppet or safety valve 33 has communication through a conduit 34 with the pipe 31. A hose 35 is connected to the conduit 34, and through this hose steam is supplied for various purposes such as cleaning and flushing gear cases and other parts of automobiles, etc., as above indicated.

When it is desired to introduce water into the boiler 17, steam under pressure is directed from the pipe 31, through a pipe 36 to an injector 37, that may be of any well-known form and to which water is supplied through a supply pipe 38 that may be temporarily connected to a suitable source of supply (not shown). From the injector 37 the water flows to the boiler through the connection 21 and the nipple 28.

Further, with respect to the burner and the fuel supply therefor, the flow through the conduit 13 to the pilot tip may be controlled by a valve 39. This valve may or may not be closed during the time that the valve 14' is opened and fuel is being consumed at the burner 9. If the valve 39 is left open, and the fuel blast emitting from the burner 9 blows out the pilot flame, the pilot will be re-ignited from the burner 9 upon closing of the valve 14' to cut off the main supply of fuel. While the pilot tip 14 is shown extending horizontally, it will be obvious that it can be disposed vertically, if desired.

An important feature of my invention resides in the provision of means such as the burner tip 14 for maintaining a pilot flame as above explained. It is difficult and perhaps impossible to maintain a pilot flame in connection with liquid fuel as heretofore supplied under pressure, with the fuel for the pilot supplied directly from the source of main fuel supply, and I have overcome this

difficulty by means of the arrangement above shown and described, wherein the fuel line is under constant pressure, as distinguished from the intermittent pressure devices of the prior art.

I claim as my invention:

1. A steam generator comprising a boiler casing, a boiler within said casing, two spiral coils surrounding said boiler and communicating therewith at their upper ends, apertured extensions on said boiler, at diametrically opposite points adjacent to the bottom thereof, and each having connection with the lower end of one coil, an inlet nipple extending through the wall of the casing and connected to one of said extensions, a nipple extending through said wall and connected to the other extension, and a water gage connected to the last-named nipple and to the upper portion of the boiler, the said nipples serving to support the boiler within the casing.

2. A steam generator comprising a boiler casing, a boiler within the casing, apertured extensions on the boiler at diametrically opposite points adjacent to the bottom thereof and at opposite points adjacent to the top thereof, nipple-like members extending through the wall of the casing and connected to said extensions, one of the lower nipple members serving as a water inlet, a water gage connected at one end to the other lower nipple member and at its other end to one of the upper nipple members, and two spiral coils each having connection with one of the upper and one of the lower extensions, the said nipples serving to support the boiler within the casing.

In testimony whereof I, the said SAMUEL PAUL have hereunto set my hand.

SAMUEL PAUL.
